UNITED STATES PATENT OFFICE.

FRED LOBNITZ, OF RENFREW, SCOTLAND.

APPARATUS FOR BREAKING ROCKS UNDER WATER.

SPECIFICATION forming part of Letters Patent No. 789,981, dated May 16, 1905.

Application filed February 18, 1905. Serial No. 246,251.

To all whom it may concern:

Be it known that I, FRED LOBNITZ, engineer and ship-builder, a subject of the King of Great Britain, residing at Clarence House, Renfrew, Scotland, have invented certain new and useful Improvements Connected with Apparatus for Breaking Up or Cutting Rocks, Stones, or Earth Under Water or on Dry Land, of which the following is a specification.

10 This invention relates to apparatus which is generally known as "rock-cutting" apparatus for cutting or breaking up rocks, boulders, stones, hard earth, and such like whether under water or on dry land.

15 The present invention is a development of my prior invention, No. 707,128, dated August 19, 1902. Under my prior invention aforesaid the natural slackening or kinking of the hoisting-rope which occurs each time the 20 cutter strikes the rock is utilized to actuate mechanism whereby the clutch of the hoisting-winches is instantaneously and automatically applied so as to prevent the hoisting-rope running out unduly and to enable the winch 25 to immediately begin raising the cutter again for another blow. The arrangement was carried out under my prior invention by means of an arm or lever which was pivoted on the winch and provided with a roller which rested 30 against the hoisting or winding rope. The arm or lever was connected, by means of a rope, to a weighted lever which was so arranged as to be capable of applying the clutch of the winch, with the result that when the 35 hoisting or winding rope slackened or kinked at the winch the weighted lever fell and applied the clutch. I have found in practice that it is more advantageous to take advantage of the kink which takes place near the upper 40 end of the cutter each time the latter strikes the rock, so as to give, if anything, a more speedy and accurate action and also to do away with the arm or lever on the winch, which was found to be in the way of the person operating 45 said winch.

My present invention may be carried out in various ways, according to the nature and structure of the rock-cutter; but I have shown on the drawings annexed hereto, by way of

illustration or example, a simple method of 50 carrying out the invention in connection with an ordinary floating rock-cutter barge.

On the drawings, Figure 1 shows the rock-cutting barge in side elevation. Fig. 2 is a plan of the barge. Fig. 3 is a vertical section of the barge, taken through the central well thereof. Figs. 4 and 4^a show a modified arrangement of the invention. Fig. 5 shows another modification.

a represents the barge; *b* *b'* *b*², the sheer-legs; *c*, the hoisting-winches; *d*, the cutter; *e*, the usual hoisting-rope, and *f* the steam-generator.

Under this invention the sheer-legs are provided with projecting brackets *g* *g*, to which 65 are hinged or pivoted two depending arms or links *h* *h*, which carry near their lower ends a spindle *i*, on which a roller *i'* is fitted so as to revolve freely. This roller, as will be seen, bears against the hoisting-rope at a point 70 above the upper end of the cutter. The lower ends of the depending links *h* have wire or other ropes *j* *j* attached to them, and these ropes pass over pulleys *k* *k* on the leg *b*² and then down over pulleys *l* *l* through holes in 75 the deck and are connected to a lever *m*, hinged or pivoted at *n* to a cross bulkhead or post *o*. The lever *m* is connected, by means of a rope *p*, to the clutch-operating lever *q* of the winch and also, by means of a rope *r*, to 80 a weight *s*, which is suspended from the lever. With this arrangement it will be readily understood that so long as the hoisting-rope *e* of the cutter is taut the lever *m* is retained in the horizontal position and the 85 clutch of the hoisting-winches is kept out of gear; but immediately the cutter strikes the rock and the hoisting-rope *e* slackens above the cutter as a consequence the weight *s* comes into action and instantaneously applies the 90 clutch of the winch by actuating the winch-lever *q*, so that the winch may at once commence to raise the cutter for another blow.

The weight *s*, lever *m*, &c., being below the deck of the vessel form no obstruction whatever to persons moving about on the deck or to the man operating the winch. Moreover, owing to the weight *s* causing the roller *i'* to

bear with considerable pressure against the hoisting-rope at a point above the cutter immediately the hoisting-rope slackens the clutch is positively and instantaneously applied.

- In the modified arrangement Fig. 4 the ropes *j* are connected to a forked bar *w*, (shown in front view, Fig. 4^a,) which again is connected, by means of a rope *v* passing over a pulley carried by a projecting bracket *x* on the winch-frame, to the clutch-actuating lever *q* of the winch and from thence to a weight *s*, as before. As will be readily understood, this arrangement will operate in the same manner as the arrangement Figs. 1, 2, and 3, the lever *m* being merely dispensed with and the rope *v* connected direct to the clutch-operating lever.

Although I have mentioned a weight *s* as being employed for actuating the clutch-lever, it is evident that one or more powerful springs (suitably connected to the lever *m* in the arrangement Figs. 1 to 3 or to the lever *q* in the arrangement Fig. 4) may be used instead of the weight. Such a spring arrangement is shown at Fig. 5, where *z* represent springs connected to the lever *m*.

Having now fully described my invention, what I claim, and desire to secure by Letters

30 Patent, is—

1. In rock-cutting apparatus the combination of a cutter, a hoisting-winches, winding means connecting the cutter with the winch, a structure from which the cutter is suspended, a clutch on the winch, means for operating the clutch, and a device arranged on the structure for operating said clutch-operating means whenever the winding means slackens.

2. In rock-cutting apparatus the combination of a cutter, a hoisting-winches, winding means connecting the cutter with the winch, sheer-legs from which the cutter is suspended, a clutch on the winch, means for operating the clutch and a device arranged on the sheer-legs for operating said clutch-operating means whenever the winding means slackens.

3. In rock-cutting apparatus the combination of a cutter, a hoisting-winches, winding means connecting the cutter with the winch, a structure from which the cutter is suspended, a clutch on the winch, means for operating the clutch and a device arranged on the structure for automatically operating said clutch-operating means whenever the winding means slackens.

4. In rock-cutting apparatus the combination of a cutter, a hoisting-winches, a hoisting-rope connecting the cutter with the winch, a structure from which the cutter is suspended, a clutch on the winch, means for operating the clutch and a device on the structure which bears against the hoisting-rope and whenever

the latter slackens automatically operates the clutch-operating means.

5. In rock-cutting apparatus the combination of a cutter, a hoisting-winches, a hoisting-rope connecting the cutter with the winch, a structure from which the cutter is suspended, a clutch on the winch, means for operating the clutch and a device suspended from the upper part of the structure and which bears against the hoisting-rope and whenever the latter slackens automatically operates the clutch-operating means.

6. In rock-cutting apparatus the combination of a cutter, a hoisting-winches, a hoisting-rope connecting the cutter with the winch, a structure from which the cutter is suspended, a clutch on the winch, means for operating the clutch, a device on the structure and which bears against the hoisting-rope, a weight connected with the clutch-operating means, and a rope connecting said weight with the said device.

7. In rock-cutting apparatus, the combination of a cutter, a hoisting-winches, a hoisting-rope connecting the cutter with the winch, a structure from which the cutter is suspended, a clutch on the winch, means for operating the clutch, a device suspended from the upper end of the structure and which bears against the hoisting-rope, a lever, a weight connected with the clutch-operating means and with the lever, and a rope connecting said lever with the said device.

8. In rock-cutting apparatus the combination of a cutter, a hoisting-winches, a hoisting-rope connecting the cutter with the winch, a structure from which the cutter is suspended, a clutch on the winch, means for operating the clutch, a roller suspended by links from the structure and bearing against the hoisting-rope, a lever, a weight connected with the clutch-operating means and with the lever, and a rope connecting said lever with the said device.

9. In rock-cutting apparatus the combination of a cutter, a hoisting-winches, a hoisting-rope connecting the cutter with the winch, a structure from which the cutter is suspended, a clutch on the winch, means for operating the clutch, brackets on the structure, links depending from the brackets, a roller carried by said links, a lever, ropes connecting said links to the lever, a weight suspended from the lever and means for connecting said lever to the clutch-operating means, substantially as described.

In testimony whereof I affix my signature in presence of two witnesses.

FRED LOBNITZ.
